HOUSING FOR SEWAGE PUMP STATION

Simpson V. Prator, P.O. Box 117, Mineral Wells, Tex.

Filed July 24, 1961, Ser. No. 66,041

Term of patent 14 years

(Cl. D13—1)

FIG. I

FIG. II

FIG. III

FIG. IV

FIG. I is a top plan view of the housing for sewage pump station, showing my new design;

FIG. II is an end elevational view taken from the left end of FIG. I;

FIG. III is an end elevational view taken from the right end of FIG. I; and

FIGURE IV is a side elevational view. The opposite side is substantially like the side shown.

I claim:

The ornamental design for a housing for sewage pump station, substantially as shown.
